Primary Examiner — Susan Moon Lee*(74) Attorney, Agent, or Firm* — Albert Bordas, P.A.(57) **CLAIM**

The ornamental design for a food bowl for pets, as shown and described.

DESCRIPTION

FIG. 1 is a top plan view of a food bowl for pets;
FIG. 2 is a front elevational view thereof, the rear elevational view being a mirror image thereof;
FIG. 3 is a bottom view thereof;
FIG. 4 is a left elevational view thereof,
FIG. 5 is a right elevational view thereof;
FIG. 6 is an isometric view thereof; and,
FIG. 7 is an exploded view thereof, wherein one bowl is shown detached.
The claimed food bowl for pets is used to keep ants and other insects away from pet food placed therein.
